UNITED STATES PATENT OFFICE.

JOHN S. NIXON, OF RACINE, WISCONSIN.

WINDOW FOR AUTOMOBILES.

1,288,139.

Specification of Letters Patent. Patented Dec. 17, 1918.

Application filed August 12, 1916. Serial No. 114,513.

To all whom it may concern:

Be it known that I, JOHN S. NIXON, a citizen of the United States, residing at Racine, in the county of Racine and State 5 of Wisconsin, have invented a certain new and useful Improvement in Windows for Automobiles, of which the following is a full, clear, concise, and exact description.

This invention relates to improvements in 10 windows for automobiles.

The general object of the invention is to provide a detachable window which may be readily and securely fastened in place on the door or other part of the automobile, without 15 using screws or other permanent fastening means, and which may be detached with equal ease and stored in some convenient part of the automobile.

The invention is particularly adapted for 20 use with what is known as the permanent roof type of body, although it is not limited to such use. In a body of this type, it is desirable to dispense with the windows a great proportion of the time. To accomplish 25 this object, it has been proposed heretofore to hinge the windows so that they may be swung down, out of the way. However, this arrangement has various obvious disadvantages which are overcome in the 30 present invention, one embodiment of which is illustrated in the accompanying drawings.

Figure 1 is an elevation of part of an automobile door showing a portion of the window detachably secured thereto in accordance with the invention.

Fig. 2 is a sectional elevation thereof on the line 2—2 of Fig. 1.

The window may be of any suitable outline, to adapt it to the particular type of 40 body for which it is intended, and consists of a sash 1 carrying the usual pane of glass 2. The window is supported on the top of the automobile door 3 by means of metal arms 4, the lower ends of which constitute 45 arms 4, the lower ends of which receive within openings 5 in said door. Each of the arms 4 forms part of an integral casting, the upper end of which has the form of a reinforcing member or brace 6 secured to the window sash by screws 50 7 or other suitable means. Said casting has a V-shaped rib or projection 8 thereon, adapted to fit in a corresponding groove in the upper end of a casting 9, the latter being secured to the automobile door by means 55 of suitable screws or other fastening means, and being designed to reinforce the door

framing from various different angles. The upper side of the door is provided with a molding 10, made preferably of steel, over which fits a rubber strip 11, the latter being secured to and carried by the bottom of the window sash 1. The rubber strip diminishes the jar and vibration of the window and renders the latter both noiseless and waterproof at the joint. To aid in securing the window in place, a spring bolt 12 is provided, the upper curved end 13 of which fits over the lower hook-shaped end of the arm 4, and exerts a downwardly inclined pressure thereon, which holds the 60 latter against the casting 9 and also holds the rib 8 firmly in the groove in the upper part of said casting. Said bolt is impelled downwardly by a spring 14 confined between a bracket 15, integral with the casting 9, 65 and a nut 16 having screw-threaded engagement with said bolt. The adjustment of the nut permits the tension of the spring to be adjusted. The lower reduced end of the bolt 17 passes through an opening in a second bracket 18 at the lower end of said casting, whereby said spring rod is guided in its vertical movement. The outer end of the bracket 15 is extended upwardly somewhat to prevent twisting of the spring bolt 70 12 about its vertical axis.

To secure the window in place on the door, the lower ends of the arms 4, of which there are preferably two, one at each lower corner of the window, are inserted through 90 the openings 5 with the window in inclined position and the ribs 8 are then forced over the rounded projection adjacent to the grooves in the top of the castings 9, thereby raising the rubber strip 11 over the molding 10, after which said ribs snap into place and the rubber strip snaps over the molding, due to the action of the spring bolt.

It will be seen that the window is rigidly 100 and firmly held in position on the door without requiring a number of auxiliary fastening devices. The fastening means being concealed within the door, the appearance of the latter is not detracted from. Furthermore, the castings 9 on the door frame are made in such a manner that they do not interfere with the upholstery on the inside of the doors. The window is held with such rigidity that no fastening 105 at the top thereof is required.

When the windows are not in use, they

are simply lifted off and stored in any convenient place. If it is desired to carry them in the car, they may be stored, for example, in the pockets provided in the rear 5 of the upholstery.

It will be seen that by virtue of the construction described, automobile windows may be equipped so as to be detachably applied in the manner described to ordinary 10 touring cars or to other types of automobile bodies. It is apparent that the window need not necessarily be applied to a hinged member, such as a door, but may be applied to the side of the body as well, 15 to provide a closed car, or it may be applied to the sides of the body, without necessarily being applied to the doors. The term "window", as used throughout the specification and also in the appended claims, is intended 20 to include side curtains, as it is obvious that the members 6 might, if desired, be used as standards for the support of such curtains as well as for the support of a rigid window, such as illustrated in the 25 drawings.

It is also obvious that various changes may be made in the details and relative arrangement of parts described herein without departing from the spirit of the invention.

Having thus described my invention, what I claim as new and desire to secure by Letters Patent of the United States is:

1. The combination with an automobile 35 door having an opening in one face thereof and a groove offset from the top edge thereof, of a window having a projection arranged to fit within said groove and having an extension arranged to pass through the 40 opening in said door, and means concealed within said door coöperating with said extension for holding said projection in said groove.

2. The combination with an automobile 45 door having openings through the inner face thereof, of a window having a cushioning strip along the bottom of its sash which rests on the top of said door, members secured to said sash and arranged to project outwardly, downwardly and inwardly through said openings, and spring bolts within said door arranged to hold said members and hence said window in place.

3. The combination with an automobile 55 door having a molding on the top, of a window having a rubber strip on the bottom thereof which fits over said molding, arms offset from said window projecting downwardly with hooks at their lower ends and 60 spring catches within said door adapted to coöperate with said hooks to retain said window in position.

4. The combination with an automobile door frame, of a casting for reinforcing the 65 latter, said casting having an opening in

one wall thereof and having brackets through which a spring bolt passes, an adjustable nut on the latter and a spring between said nut and one of said brackets.

5. The combination with an automobile 70 window, of an L-shaped reinforcing member secured to one corner thereof, an arm extending downwardly from said reinforcing member having a V-shaped member at its upper end and having a hook at its lower 75 end.

6. The combination with an automobile door having an opening therein, of a vertically movable spring bolt within said door, a window having an offset arm extending 80 downwardly therefrom with a hook at its lower end adapted to be hooked through said opening and to be engaged by said spring bolt when the window is in inclined 85 position, and coöperating means on said door and window for holding the latter against side movement when swung to vertical position, said bolt and hook serving to maintain said coöperation.

7. The combination with an automobile 90 body having a molding thereon, of a window having a groove in the lower part thereof to fit said molding, a groove in said body adjacent to said molding, a rounded edge adjacent to said groove, a rib carried by said window and arranged to fit said groove, extensions on said window, and means within said body arranged to exert a yielding pressure on said extensions, said parts being so disposed that as said window is swung upwardly from inclined to vertical position, said rib rides over said rounded edge whereby the groove in said window is lifted over said molding and thereafter snaps downwardly over the same as said rib snaps into 105 said groove.

8. The combination with an automobile window, of a reinforcement secured to one corner thereof, said reinforcement being provided with an arm having a V-shaped member at one end and having a hook at its other end.

9. In an automobile body, the combination with a door, of a window arranged to rest thereon, a support carried by said door 115 and offset therefrom, an offset projection carried by said window and adapted to rest on said support, an arm integral with said projection, and means coöperating with said arm to lock said projection in engagement 120 with said support whereby said window is maintained in position on said door.

10. In an automobile body, the combination with a door, of a window arranged to rest thereon, an arm carried by said window 125 and extending downwardly therefrom over the inner face of said door, and a spring catch arranged within said door, the lower end of said arm being bent inwardly and adapted to extend through an opening in the 130

face of said door to thereby engage said spring catch whereby said window is maintained in position on said door.

11. The combination with an automobile door having openings in one face thereof, of a plurality of grooved supports offset from the top edge of said door, a plurality of standards adapted to rest on said supports and being provided with projections arranged to engage within the grooves thereof, downwardly extending arms carried by said

standards and adapted to extend through the openings in said door, and means concealed within said door coöperating with said arms for holding said projections in said grooves.

In witness whereof, I hereunto subscribe my name this 7th day of August A. D., 1916.

JOHN S. NIXON.
